FRANZ HUND, OF CLEVELAND, OHIO

VALVE SPRING COMPRESSING TOOL

Application filed January 29, 1932. Serial No. 589,671.

This invention relates to tools, particularly the hand-operated mechanic's tools for relieving the pressure of internal combustion engine valve springs.

As is well known, the valves of internal combustion engines are maintained upon their seats by springs and when it is desired to relieve the pressure of the spring for any purpose in connection with inspecting or repairing the engine, some form of a force multiplying tool must be employed to overcome the great resilient force exerted by the spring.

In some types of internal combustion engines such as those used to propel airplanes, an overhead rocker arm is employed to operate the valves, the arm being rocked by the thrust of a longitudinally movable cam-operated push rod, and the thrust of the rod being transmitted through the rocker arm to compress the valve spring and to open the valve.

In the practice of inspecting and caring for such airplane engines, it is frequently necessary to remove the said push rod to examine and/or to lubricate the same, and in order to effect this operation, the valve spring must be compressed to relieve the longitudinal pressure of the rocker arm on the end of the push rod.

Tools have been devised heretofore for this purpose, but besides being inefficient and inconvenient to use, have exposed the user to the danger of injury. Any tool for this purpose must be applied to the parts of the engine as built by the manufacturer and due to the limited space in which such a tool may be operated and to the usual shape of the parts to be engaged by the tool and due to other causes which will be understood by those skilled in this art, tools heretofore employed for this purpose frequently slip when the relatively great forces necessary to compress the spring are applied thereto, and such slippage often occurs while the operator is

in the act of removing or inspecting the push rod and the sudden release of the spring thus effected and the extremely rapid movement of the same and of the parts associated therewith have heretofore caused serious injury 50 to mechanics either by the shock of contact with such suddenly released and rapidly moving part, or as in some instances occurs, by the pinching of the mechanic's hand or finger between portions of the relieved rocker 55 arm and push rod.

It is therefore one of the objects of this invention to provide a tool adapted to be applied to internal combustion engines such as airplane engines to compress the valve 60 spring thereof and to correspondingly relieve the push rod thereof which will be efficient and convenient to use and operating in an improved manner.

Another object of my invention is to provide such a tool which may be put in position to effect its said operation and then secured in said position by conveniently operable means to prevent accidental displacement from said position.

Another object is to provide such a tool which, after having performed its valve spring compressing operation, may be, by means of associated conveniently operated parts, maintained in said position whereby 75 both hands of the user may be free to perform the work of repairs or inspection to effect which the spring is compressed.

Another object is to provide generally an improved hand-operated tool for relieving 80 the tension of the valve springs of internal combustion engines.

Another object is to provide a tool of the class just referred to having auxiliary means to maintain the tool in valve-spring-tension-relieving position.

Other objects will be apparent to those skilled in the art to which my invention appertains.

My invention is fully disclosed in the fol- 90

lowing description taken in connection with the accompanying drawing, in which:

Fig. 1 is a side elevational view of a tool embodying my invention and showing one mode of its application to an internal combustion engine to compress a valve spring thereof, and showing in connection with the valve spring, a mode of relieving the longitudinal thrust on a push rod of the valve mechanism;

Fig. 2 is a cross-sectional view taken from the plane 2 of Fig. 1 and drawn to a larger scale;

Fig. 3 is a view taken from the plane 3 of Fig. 1 and drawn to the scale of Fig. 2;

Fig. 4 is a view similar to Fig. 1 but showing a modification.

Referring to the drawing, I have shown in relatively light lines a part of the housing 20 and valve construction of an internal combustion engine such as an airplane engine and comprising a housing 1, a valve 2 having a valve stem 63 longitudinally reciprocable in the housing. The valve 2 is adapted to be forceably resiliently held against the valve seat 3 by a compression helical spring construction shown generally at 4. The valve stem is provided with a spring compressing head 5 terminating upwardly in a ball 6 seated in a socket 7 on the end of an arm 8 of a rocker arm 9 pivotally supported on suitable bearings at 10 and having a relatively short arm 8'.

The arm 8' is provided with socket 11 in which may be seated the ball 12 formed or provided on the upper end of a push rod 13, the lower end of which is not shown but which, in a manner well known to those skilled in this art, communicates with a cam 40 or like device which periodically gives an upward longitudinal thrust to the rod 13.

By this construction as is well known, an upward thrust on the rod 13 will rock the rocker arm 9 clockwise around its pivot 10 and through the ball and socket joint 6-7 give a downward thrust to the valve stem 63 to open the valve 2-3 against compressive force of the spring 4; and when the thrust on the push rod 13 is relieved, the spring 4 will retract to force the valve 2 upwardly against its seat 3 and to rock the arm 9 counterclockwise maintaining the ball and socket joint 12-11 in constant mutually engaged condition.

In the construction illustrated, a lubricant nipple 14 is provided in the end of the arm 8 to admit lubricant to the ball and socket joint 6-7, and preferably the nipple 14 is of the type having an upwardly extending generally conical tip 15 for the reception of the nozzle of the lubricant gun.

As will be understood, both ball and socket joints 6-7 and 11-12 are, in the normal operation of the mechanism, maintained in pressure engagement with each other by the

reaction of the spring 4, the ball and socket joint 11-12 being illustrated in relieved or disassociated position for a purpose to be described.

In engine housings of the general type 70 illustrated in the drawing, an overhanging cover 16 is provided, generally integral with the housing 1, and overhanging the rocker arm 9 or a portion thereof. A chamber indicated generally at 17 is thus provided for 75 housing the rocker arm 9 and its associated parts just described, and an open side of the chamber, indicated at 18, may be closed by a removable cover in a well known manner.

The tool embodying my invention is illustrated in Fig. 1 in generally relatively heavy lines at 20 and is illustrated and will be described in a preferred position of use. The tool 20 comprises a straight handle portion 21 bent as at 22 generally U-shaped and having in a lever portion 23 formed from the leg of the U opposite the handle portion 21. The lever portion 23 is relatively short and toward the end thereof may be tapered as indicated at 24. Preferably, the tool thus far described is made from round steel stock and the tapered portion 24 is provided by flattening the leg 23 on its inner side.

If desired, but not essentially, the bend of the tool indicated at 22 may be strengthened 95 to prevent divergence or convergence of the legs 20 and 23 by a tie portion 26.

One suitable manner of applying the tie portion 26 is by the welding process. On the underside of the leg 23 as viewed in the 100 drawing and relatively remote from the outer end of the leg 23 I provide a recess 28 and adjacent thereto a projection or nipple 29.

Mounted on the straight handle portion 21 is a slider 30 comprising a hollow tubular portion 31 telescoped with and slidable upon the handle portion 21 and having a depending web 32 terminating at its lower end in a generally outwardly concave segmentally tubular jaw 33. The jaw is inclined toward the bend 22 and toward the handle 21 and due to its segmentally tubular form provides a pair of gripping edges 34-34 which are preferably serrated transversely as shown at 35. The handle portion 21 is provided laterally thereof with a plurality of ratchet teeth 36 and cooperating therewith is a pawl 37 formed on the end of a lever 38 pivotally mounted as at 39 between a pair of lugs 40-40 extending laterally from the tubular portion 31 of the slider. The lever 38 is provided with a handle portion 41, suitably formed to be engaged by a thumb or finger of the user, and a spring 42 abutting at one end upon the underside of the lever 38 and at its other end upon the wall of the tubular portion 31, maintains the lever 38 rotated around the pivot bearing 39 to engage the pawl 37 in the ratchet teeth 36.

In the operation of my invention thus far 130

described, the operator grasps it by the handle portion 21 or by both the handle portion 21 and the bend portion 22 and inserts the tapering leg 24 thereof through the opening 5 indicated at 18 and above the rocker arm 9 until the end of the leg 23 engages the housing 1 as at 50 on the inner face of the overhanging housing portion 16. The bend 22 is then lowered or, that is to say, rocked clockwise around the point 50 until the recess 28 of the tool is engaged by the nipple portion of the lubricating nipple 14. The operator then exerts an upward pull on the handle portion 21 which rocks the tool around the point 50 15 and exerts a downward thrust on the lubricant nipple 14 and therefore a clockwise torque on the rocker arm 9 and compresses the spring 4. This places the parts in the position shown in the drawing with the exception of the slider 30, the handle portion 21 having been moved from the broken line position to the solid line position.

The operator now, while holding the lever in its spring-compressing position, moves the slider 30 along on the handle portion 21 toward the bend 22 and until one or both of the jaws 34 engage or wedgingly jam upon a portion of the housing 1, such position being illustrated in the drawing. During this sliding movement of the slider 30, the pawl lever 38 may be depressed against the spring 42 and at the end of the said sliding operation the pawl lever 38 may be released to engage the pawl 37 with a suitable tooth or tooth 36 to prevent backward movement of the slider 30. Or, as an alternative mode of operation, the shape of the tooth spaces between the teeth 36 and the shape of the pawl 37 may be so correlative provided that upon 40 the above mentioned sliding movement given to it by the slider 30, the pawl 37 will ratchet over the teeth 36 and at the end of the sliding movement automatically drop into the nearest adjacent space between the teeth 36 and 45 locking the slider 30 against rearward slipping movement.

The operator may now release the force on the handle 21 and inasmuch as the slider will prevent counter-clockwise rotation of the tool as a whole around the point 50, it will be maintained in a clockwise position maintaining the spring 4 compressed.

With the rocker arm 9 in its clockwise rotated position illustrated, the ball of the push rod 13 is relieved from the socket 11 and the push rod may be removed in a well known manner to inspect and/or lubricate or replace the same according to well known practice.

Upon removing the tool by the reverse of the operations above described, that is, by first removing the slider and then permitting the handle 21 to be moved counter-clockwise around the point 50 by the spring 4, the ball and socket joints may again be seated upon each other without shock and the toolulti-

mately removed in a manner that will be understood.

It will be observed that while the tool is being applied to the operation of compressing the spring 4, the operator's hands may be entirely out of the danger hereinbefore referred to, and after the tool has been locked in its operative position, it is prevented from accidentally tipping sidewise or slipping from its installed position, and the operator is free to use both hands in his repair or inspection work.

In Fig. 4 I have illustrated the application of my tool to rocker arms 9' in which the socket 7' is lubricated simply by a duct 14', the upper end of which may be enlarged as at 15', and the above mentioned projection or nipple 29 on the tool may be inserted into the enlargement 15'. Otherwise the operation of the tool is the same as that hereinbefore described.

My invention is not limited to the exact details of construction shown and described. Many changes and modifications may be made therein without departing from the spirit of my invention or sacrificing its advantages.

I claim:

1. In a tool of the class described, an unequal legged U-shaped body, a portion of the short leg adjacent the U-bend being adapted to engage a portion of a valve construction, a head slidable on the long leg and having a jaw portion overlapping the short leg.

2. In a tool of the class described, an unequal legged U-shaped body, a portion of the short leg adjacent the U-bend being adapted to engage a portion of a valve construction, a head slidable on the long leg and having a jaw portion overlapping the short leg, and a pawl and ratchet device on the long leg and head to removably fix the position of the head on the said leg longitudinally thereof.

3. In a tool of the class described, a U-shaped body comprising a long leg and a short leg, the long leg constituting a handle, the short leg being adapted to be inserted into an internal combustion engine valve housing and to engage its end upon an inner overhanging portion of the housing, and being provided with a non-slipping valve construction engaging portion spaced from said end, a head slidably mounted on the long leg and having a laterally projecting jaw portion movable into engagement with an external portion of the housing to maintain the handle in spaced relation to the housing.

4. In a tool of the class described, a U-shaped body comprising a long leg and a short leg, the long leg constituting a handle, the short leg being adapted to be inserted into an internal combustion engine valve housing and to engage its end upon an inner overhanging portion of the housing, and be-

ing provided with a non-slipping valve construction engaging portion spaced from said end, a head slidably mounted on the long leg and having an inclined laterally projecting 5 jaw portion movable into engagement with an external portion of the housing to maintain the handle in spaced relation to the housing.

5. In a tool of the class described, a 10 U-shaped body comprising a long leg and a short leg, the long leg constituting a handle, the short leg being adapted to be inserted into an internal combustion engine valve housing and to engage its end upon an inner 15 overhanging portion of the housing, and being provided with a non-slipping valve construction engaging portion spaced from said end, a head slidably mounted on the long leg and having a laterally projecting jaw portion 20 movable into engagement with an external portion of the housing to maintain the handle in spaced relation to the housing, and inter-engaging locking parts on the head and handle operable to prevent movement of the 25 head on the handle in one direction.

6. In a tool of the class described, a U-shaped body comprising a long leg and a short leg, the long leg constituting a handle, the short leg being adapted to be inserted 30 into an internal combustion engine valve housing and to engage its end upon an inner overhanging portion of the housing, and being provided with a non-slipping valve construction engaging portion spaced from said 35 end, a head slidably mounted on the long leg and having a laterally projecting jaw portion movable into engagement with an external portion of the housing to maintain the handle in spaced relation to the housing, and 40 inter-engaging locking parts on the head and handle operable to prevent movement of the head on the handle in the direction away from the bend.

7. In a tool of the class described, a U-shaped body comprising a long leg and a short leg, the long leg constituting a handle, the short leg being adapted to be inserted into an internal combustion engine valve housing and to engage its end upon an inner 50 overhanging portion of the housing, and being provided with a non-slipping valve construction engaging portion spaced from said end, a head slidably mounted on the long leg and having a laterally projecting jaw 55 portion movable into engagement with an external portion of the housing to maintain the handle in spaced relation to the housing, and a ratchet mechanism on the head and handle operable to prevent movement of the 60 head on the handle in one direction.

8. In a tool of the class described, a body comprising a long leg and a short leg extending generally in the same direction, the long leg constituting a handle, the short leg being 65 adapted to be inserted into an internal com-

bustion engine valve housing and to engage its end upon an inner overhanging portion of the housing, and being provided with a non-slipping valve construction engaging portion spaced from said end, a head slidably mounted on the long leg and having a laterally projecting jaw portion movable into engagement with an external portion of the housing to maintain the handle in spaced relation to the housing.

In testimony whereof he hereunto affixes his signature this 26th day of January, 1932.
